TYPEWRITER

Kelley D. Evans, Hamilton, Ohio, assignor of
one-half to C. E. Hooven, Hamilton, Ohio

Application September 20, 1937, Serial No. 164,730

3 Claims. (Cl. 197—66)

This invention relates to typewriters and particularly to improvements in the carriage return and line spacing mechanisms.

The subject matter of this application is a portion of a complete typewriter other parts of which are claimed in a companion application Serial No. 164,729 filed of even date herewith (now Patent No. 2,158,066).

In this typewriter I employ a power-operated actuator for accomplishing under the control of the operator the major portion of the functions or operations required in typewriting, including the swinging of the type bars to printing position, letter and word spacing, case shifting, line spacing, and carriage return.

The principal object of the present invention is to do away with the necessity of the operator's hand being lifted from the keyboard in bringing about the line spacing and the carriage return, and to provide an improved power-operated mechanism controlled by a key of the keyboard for the performance of these operations.

A further object is to provide a carriage return mechanism which is associated with and forms a part of the line spacing mechanism and which functions to first line-space the platen and then return the carriage to its righthand position.

It is a feature of the invention also that after the carriage is returned to its righthand position additional line spacing movements may be imparted to the platen by the power-operated mechanism initiated by the depression of the carriage return key, or, if desired, by operating the usual line spacing lever.

The invention may be briefly summarized as consisting in certain novel details of construction and combinations and arrangements of parts which will be described in the specification and set forth in the appended claims.

In the accompanying sheets of drawings in which I have shown an embodiment which operates with high efficiency,

Fig. 1 is a vertical sectional view of the typewriter;

Fig. 2 is a rear view;

Fig. 3 is a view similar to Fig. 1 with parts in elevation but showing the position that the parts of the power mechanism occupy when the clutch is engaged and the actuator is in its lowermost position; and

Fig. 4 is a plan view showing a portion of the platen and a portion of the line spacing mechanism which is located at the upper lefthand end of the machine.

I will first refer to those portions of the type-

writer which are claimed in my companion application referred to, but since they form portions of the complete typewriter, I have illustrated them, but as they are not claimed herein, I will describe them only briefly.

The machine includes a main frame 10 at the bottom of which is a sub-frame 11 which, however, may be an integral part of the main frame. At the front is a keyboard composed of the usual keys 12 and the space bar 13, there being in the keyboard keys corresponding to all the printing characters and, additionally, a case shift key and a carriage return and line spacing key.

The keys 12 are on key levers 12a mounted to swing on a fulcrum rod 15 in a comb 16 which in this instance is supported by the sub-frame 11. The key levers have downward extensions 17 which at their lower ends are extended rearwardly. Associated with the key levers 12a are so-called slide levers 18 which are normally engaged by the lower rearwardly projecting ends of the key levers, as shown in Fig. 1. These slide levers are adapted to be tilted rearwardly on the depression of the keys, and, after being tilted, they are adapted to be slid downwardly by the power-operated actuator to be referred to presently. Their upper ends are slotted and they are adapted to pivot on the depression of the keys around a fulcrum rod 19 and they slide in an upper comb 20 and a lower comb 21 both supported by the sub-frame. They are normally held in their upper forward positions shown in Fig. 1 by springs 22 connected to forward extensions 18a of the slide levers and to a plate attached to the bottom of the comb 16. All the character keys and their key levers are mechanically independent of the type bars and the other keys of the keyboard are mechanically independent of the parts or mechanisms which they control. However, the slide levers 18 are mechanically connected to the type bars, one to the universal bar, one to the case shift, and one to the mechanisms for effecting the line spacing and the carriage return for, as will be subsequently explained, the depression of the keys simply tilts or swings the slide levers rearwardly about the fulcrum rod 19 to a position to be engaged by the power-operated actuator which slides them downwardly to accomplish the typewriting and other operations. All of the slide levers have rearward extensions 18b and the extensions of all of these slide levers except the one which causes the operation of the line spacing and carriage return mechanisms are connected to adjustable links 23 which extend upwardly

from the rearward extensions 185. The slide levers which are associated with the character keys are connected by the links 23 to levers 24 the forward ends of which slide in a comb 25 just at the rear of the fulcrum rod 15 and their rear ends are fulcrumed on a fulcrum rod 26 extending across the main frame, these levers being mounted in a manner similar to the ordinary key levers of a typewriter. These levers 24 are connected by sub-levers 27 to type bars 28 which are adapted to be swung to printing position and are mounted on a fulcrum wire 29 mounted in the usual segment 30. This segment receives the usual universal bar 31 which is operated each time a type bar is swung to printing position to actuate the escapement mechanism which is not here shown but which is preferably such as is customarily employed in standard typewriters.

20 I have shown the platen conventionally at 32 mounted in the usual manner on the cylinder shaft 33 journaled in the usual fashion in the carriage a portion of which is shown at 34, the carriage being mounted in the carriage frame 35 a portion of which is shown in the drawings and which may be of usual construction. The carriage is supported, as is customary, on a way rod 36 and on a front rod 37. The front rod 37, while it performs the usual carriage supporting function, 30 has a special mounting and is capable of slight endwise movement for a purpose to be explained presently.

25 The platen is rotated for line spacing purposes by a ratchet 38 which is engaged by a pawl 39 pivoted to the line space plunger 40 which may be operated by the line space lever customarily employed on typewriters. It might be here stated that this plunger is adapted to be operated by the power mechanism both in connection with 40 and independently of the carriage return through the depression of the carriage return key of the keyboard, as will be explained presently.

30 The space bar 13 is mounted on a space bar shaft 14 journaled in brackets on the lower part 45 of the comb 16, and this shaft is provided with a downwardly and rearwardly extending arm 41 which engages the rear edge of one of the slide levers 18 and is connected by one of the adjustable links 23 to a lever 42 on a shaft 43 supported by the main frame 10. This shaft has an upwardly and rearwardly extending arm 44 which is connected to an arm 45 of a rock shaft 46 supported by the main frame, the rock shaft having an upper arm 47 connected to a rearward extension 48 of the universal bar. In consequence, 55 the universal bar is not only operated when the type bars are swung to printing position but may be operated by the depression of the space bar for word spacing all, however, through the movements imparted to the slide levers by the power driven actuator.

50 I have not here illustrated the case shift as it is not claimed herein but is illustrated and claimed in my companion application referred to above. As explained in my companion application, the case shift may be effected by shifting the carriage or shifting the segment, but, as illustrated in my companion application, it is accomplished by shifting the carriage through the medium of parts which engage the carriage and which are connected to one of the slide levers associated with one of the keys of the keyboard and adapted to be first tilted and then swung downwardly precisely as is the case with the slide levers associated with the other keys.

5 I employ a motor, preferably an electric motor 49, which in this instance is mounted on the rear of the sub-frame 11. The shaft of the motor is provided with two pulleys and drives constantly, as long as the motor is in operation, two belts 50 and 51. The belt 50 extends forwardly into the sub-frame and passes about a normally loose pulley forming a part of a clutch designated as a whole by the reference character 52. Inside this pulley is a hub which is mounted on a short 10 shaft journaled in bearings on the base of the sub-frame. At one end of this shaft is a crank which is adapted to swing an arm 53 mounted on a shaft 54 extending across the sub-frame. This shaft is provided at its ends with two arms 55 15 at the forward free ends of which is a normally stationary actuator 56 which, when the clutch is engaged, is adapted to swing downwardly and then upwardly where it is stopped in its uppermost position. The downward swinging movement is the power stroke of the actuator, and during this stroke it shifts downwardly one of the slide levers 18 to the position shown in Fig. 3, the particular slide lever having been tilted rearwardly by the actuation of the corresponding 20 key of the keyboard so as to bring the rearward extension or shoulder 18c beneath the actuator. When the slide lever is moved downwardly, as just stated, it passes in front of a lock bar 57 which prevents the shoulder 18c from sliding outwardly from beneath the actuator during its power stroke. As the actuator returns to its uppermost position where it stops by reason of the disengagement of the clutch, the spring 22 restores the slide lever to its previous normal position shown in Fig. 1.

25 When any of the slide levers 18 is tilted or swung rearwardly by the depression of the corresponding key of the keyboard, not only is the shoulder 18c of that slide lever moved rearwardly 30 in position to be engaged by the actuator 56, but, at the same time, the lower part of the slide lever engages and moves rearwardly a universal trip bar 58 so as to cause the engagement of the clutch 52. This trip bar extends across the 45 lower part of the machine at the rear of the slide levers and it is supported on the lower ends of two arms 59 pivotally supported by the sub-frame.

35 The clutch 52 is of the type composed of a 40 freely running outer pulley and a normally stationary hub which is adapted to be clutched to the pulley by a roller movable in a notch on the face of the hub and normally held by the clutch disengaging means in the wider part of the 45 notch so as to keep the clutch normally disengaged. When this roller is released, the springs which act on it move it forwardly into the narrow part of the notch, causing the instant engagement of the clutch. This type of clutch is 50 well known and it is thought unnecessary to illustrate the details herein particularly as it is shown in my companion application referred to above.

55 The clutch is normally held in disengaged condition by a yoke 60 which at its rear end engages in front of a pair of buttons at the outer ends of the roller of the clutch so as to retain the roller in the wider part of the slot against the action of the springs. The yoke is pivotally mounted 60 on the base of the sub-frame and is normally moved to clutch disengaged position shown in Fig. 1 by a spring 61. The front end of this yoke is beveled and it is normally engaged by a pin 62 on a spring-pressed latch 63 mounted on a 75

lever 64 connected to the rear end of a link 65 whose forward end is connected to the universal trip bar 58. When the clutch is disengaged, the latch 63 engages a pin 66 fixed to the lever 64.

5 The arrangement is such that when the universal trip bar is swung rearwardly the link 65 swings the lever 64 toward the left as the same is viewed in Fig. 1. This causes the pin 62 to cam the forward end of the yoke 60 upwardly and its 10 rear ends downwardly, tripping the clutch, but immediately after the clutch is tripped or engaged, the pin 62 passes under the lower point of the bevel at the forward end of the yoke, whereupon the yoke is restored by the spring 61 15 to its former position and again re-engages the buttons on the rotating hub so as to disengage the clutch after it has made one revolution. Meanwhile, the actuator 56 has been moved downwardly and then upwardly through one 20 cycle of movement and has been again restored to its normal stationary position shown in Fig. 1. Likewise, the trip bar and the slide lever which were previously actuated have been returned to their normal positions.

25 Coming now to the parts more directly involving the invention claimed in this application, namely, the mechanism for performing line spacing and carriage return operations, I utilize as a part of the mechanism for performing these operations 30 a stiff rail 67 (see particularly Fig. 2) which extends horizontally across the upper rear part of the machine and at opposite ends has pin and slot connections with two brackets 68 which are attached to the rear corners of the carriage frame. 35 Obviously, by reason of the pin and slot connections between this rail and the carriage frame, when the rail is moved to the left as the machine is viewed from the rear, as in Fig. 2, the rail will first move relative to the carriage a distance depending upon the length of the slots and then will move the carriage frame itself and, in fact, effect the carriage return.

For the purpose of moving the rail 67 (and the parts which are actuated by it), I employ a 40 species of normally open or disengaged clutch consisting in this instance of two rubber rollers 69 and 70 which are normally spread apart, as shown in Fig. 1, so as to be out of driving relation with the rail but are adapted to be brought 45 together so as to pinch the rail between them and thus move the rail in an endwise direction. As long as the motor is in operation, the roller 69 is rotated continuously on the upper end of a vertical shaft 71 which at its lower end is connected 50 by reduction gearing, in this instance worm gearing 72, to a short horizontal shaft 13 which is driven constantly by the belt 51 as long as the motor 49 is in operation. The upper end of the shaft is journaled in a bracket 14 which is attached to the upper rear part of the frame 10, as most clearly shown in Fig. 2, and pivoted to a portion 55 of this bracket inwardly of the shaft 71 is an arm 75 carrying the second roller 70. Beneath the rollers 69 and 70 are two gears 76 and 77 by which rotation is transmitted from the shaft 71 to the inner roller 70, the gears being partially in mesh at all times but only in full mesh when the arm 75 has been straightened, as shown in Fig. 3, so as to bring the two rollers into driving 60 engagement with the rail 67. The gear 76 is fixed to the shaft 71 and the gear 77 and the roller 70 are on a short stud which is rotatably supported in the upper end of the arm 75.

The rollers 69 and 70 are adapted to be spread 65 apart or brought together by a toggle composed

of two links 78 one pivotally connected to the lower part of the bracket 14 and the other pivotally connected to the arm 75. The center of the toggle is adapted to be pulled downwardly so as to spread the rollers and to be moved upwardly to or slightly beyond center position so as to bring the rollers into driving engagement with the rail 67 by a toggle operating rod 79 which at its lower end is connected to an arm 80 on a rock shaft 81 mounted in the rear part 10 of the sub-frame and having an arm 82 which is connected by a link 83 to the downwardly extending arm 84 of a bell crank pivoted at 85 on the sub-frame and provided with a forwardly extending arm 86 the forward end of which is directly beneath the extension 18b of the slide lever 18 which is associated with the carriage return key of the keyboard, this particular slide lever being shown in Fig. 3. It is to be noted that the extension 18b of this particular slide lever is not 20 connected by an adjustable link 23 to a lever above it as is the case with all of the other slide levers associated with the space bar 13 and with the other keys of the keyboard.

The arrangement is such that, when the carriage return key is depressed, the associated slide lever 18 is swung rearwardly as before so as to bring the shoulder 18c beneath the actuator and to swing the universal trip bar 58 rearwardly and engage the clutch 52. When this occurs, the actuator makes one cycle of movement as before, and on the power stroke shifts the slide lever 18 downwardly. As it does so, it rocks the bell crank composed of the arms 84 and 86, moving upwardly the rod 79 and straightening the toggle composed of the links 78. The rollers 69 and 70 are constantly rotating, and it might be here stated that they rotate at the same speed and in a direction to move the rod 67 to the right when the machine is viewed from the front. When the 40 toggle is straightened, the rollers 69 and 70 immediately engage the rail 67 and move it to the left as the same is viewed in Fig. 2. As before stated, due to the pin and slot connection between the rail and its supporting bracket 68, it 45 first moves relative to the carriage, and when the pins reach the end of the slots, the carriage is moved to carriage return position or until an adjustable stop 87 (see Fig. 2) on the front rod 37 engages a projection 88 on the carriage frame. When this occurs, the end of the front rod 37 50 engages the upper end of a bell crank 89 which is mounted on the righthand end of the main frame 10, as best shown in Fig. 2. This bell crank has an inwardly extending arm the inner 55 end of which is connected to a downwardly extending trip rod 90 the lower end of which passes through the forwardly projecting arm 86 of the bell crank composed of the arms 84, 86. At the lower end of the rod beneath the arm 86 the rod 60 has a shoulder preferably in the form of an adjustable nut 91 which rocks the bell crank so as to pull the rod 79 downwardly and break the toggle composed of the links 78, thus stopping the driving action of the rollers 69 and 70 on the 65 rail 67. Before this occurs, the slide lever 18 which had previously rocked the bell crank 84, 86 is out of the way and has been restored to its previous position by the associated spring 22.

The limited free movement of the rail 67 relative to the carriage frame is utilized by me for giving the platen 32 a line spacing movement, and, accordingly, I connect to the end of the rail 67 (the righthand end when the machine is viewed from the rear as in Fig. 2) an arm 92 (see par-

ticularly Fig. 4) attached to the lower end of a rock shaft 93 (Fig. 3) which is mounted in vertical position on an arm 68a of the adjacent bracket 68. The upper end of the rock shaft 93 is provided with an inwardly projecting arm 94 connected by a link 95 to the usual line space plunger 40 previously referred to, and, as before stated, normally adapted to be operated by the line space lever. In Fig. 1 I have shown the normal position of the line space plunger 40, and in Fig. 3 its position after it has been given the spacing stroke by the described mechanism equivalent to a one-space movement of the platen 32.

15 Thus it will be seen that when a character key of the keyboard is depressed, the associated slide lever is tilted rearwardly, the clutch 52 is engaged by the rearward movement of the universal trip bar 58, the actuator is given a power stroke downward, and then a return stroke which is followed by the disengagement of the clutch, and during the power stroke the type bar associated with the key which has been depressed is swung to printing position so as to cause the letter spacing through the usual escapement mechanism. For word spacing, the space bar 13 is depressed, whereupon the universal bar 31 is again actuated through the operation of the slide lever associated with the space bar and through 25 the action of the clutch and actuator, as before.

Likewise, when the carriage is to be returned, the operator simply depresses the carriage return key, causing the associated slide lever 18 to be tilted rearwardly, resulting in the engagement of 30 the clutch and the downward swinging of the actuator, but in this instance the ensuing downward movement of the slide lever rocks the bell crank 84, 86 and through the mechanism connected to it straightens the toggle and causes the rail 67 to be moved endwise. This endwise movement, as before stated, first results in a line spacing movement to be given to the platen and then the carriage is returned to its righthand position, and through the action of the front rod 35 40 on the bell crank 89 and the parts connected to it, the toggle is broken and the rollers spread out of engagement with the rail 67. As previously stated, the front rod is not mounted in fixed position in the frame 10 but is capable of 45 limited endwise movement, but this movement is opposed by a spring 96 (Fig. 2) which surrounds the lefthand end of the front rod between a shoulder on the main frame and a nut on the end of the rod. This spring cushions the blow 50 when the projection 88 on the carriage engages the adjustable stop 87 and it serves also to give a slight return movement to the carriage after its return movement is completed, resulting in the slight return movement of the bell crank 89 and the downward movement of the rod 90 (by 55 its own weight), thus lowering it to the position shown in Fig. 1 and permitting the subsequent operation whether simply for line spacing purposes or for both line spacing and carriage return.

It might be mentioned at this point also that upon the breaking of the toggle and the spread-

ing of the rollers 69, 70 the rail moves to the right the distance permitted by the length of the slots. This return movement is caused by the spring 97 (Figs. 1 and 3) which is connected to the line space plunger 40 and normally returns the plunger 40 and the line space lever as well as the pawl 39 to their normal positions. This return of the rail 67 makes it possible to impart subsequent line spacing movements by the depression of the carriage return key or both the line spacing movement and the carriage return with the line spacing movement preceding the carriage return. The depression of the carriage return key when the carriage is at its righthand position simply results in slight endwise movement of the rail 67 to the extent permitted by the length of the slots in the bracket 68. This movement imparts a line spacing movement to the platen in the manner explained, and each is followed by the necessary rocking of the bell crank 89 to break the toggle. Since the line spacing operation through the action of the power mechanism is applied to a regular line space plunger to which the line space lever is attached, the operator may effect whatever line spacing operations are desired after the carriage return by operating this lever in the usual manner.

While I have shown the preferred construction, I do not desire to be confined to the precise details shown but aim in my claims to cover all modifications which do not involve a departure from the spirit and scope of the invention.

Having thus described my invention, I claim:

1. In a machine of the character described, a frame, a carriage movable transversely thereon, and means for giving the carriage its return movement comprising an endwise movable member connected for movement with the carriage and a pair of driving members engageable with opposite sides of said member to move it endwise, and means for effecting driving engagement and disengagement of said driving members with said endwise movable member.

2. In a machine of the character described, a frame, a carriage movable transversely thereon, and means for giving the carriage its return movement comprising an endwise movable member connected for movement with the carriage, driving means on each side of said member and engageable therewith to move it endwise, and a toggle interconnecting the two driving means, and means for operating the toggle to clamp the two driving means against opposite sides of said endwise movable member.

3. In a machine of the character described, a frame, a keyboard supported by the frame, a carriage movable transversely on the frame, and means for giving the carriage its return movement comprising an endwise movable member connected for movement with the carriage, driving means on each side of said endwise movable member and engageable therewith to move it endwise, and means controlled by a key of the keyboard for effecting driving engagement of said two driving means with opposite sides of said endwise movable member.

KELLEY D. EVANS.
